T. W. HICKS

TILLER

Filed March 29, 1923

Fig. 2.

UNITED STATES PATENT OFFICE.

THOMAS W. HICKS, OF MINNEAPOLIS, MINNESOTA.

TILLER.

Application filed March 29, 1923. Serial No. 628,644.

This invention relates to improvements in tillers and more particularly to that general type illustrated and described in my prior Patent No. 1,320,469, dated November 4, 1919.

5 One of the objects of the present invention is to provide an improved tiller of the above general character, having relatively few parts and which may be inexpensively manufactured and assembled.

10 A further object is to provide a device of the above general character which will be strong and durable in construction, and reliable and efficient in use and operation.

A further object is to provide an improved 15 tiller which will more efficiently break up the soil as it is turned over by the plow and distribute the same as may be desired.

A further object is to provide a tiller shaft of the above character in which some of the 20 blades may be caused to rotate at a faster or slower speed than the others and in the same direction or in opposite directions as desired.

Other objects will be in part obvious from 25 in connection therewith in the following analysis of the invention.

The invention accordingly consists in the features of construction, the combination of parts, and in the unique relation of the various 30 members and the relative proportioning and dispositioning thereof, all as more clearly outlined herein.

To enable others skilled in the art to fully comprehend the underlying features thereof 35 in order that they may embody the same, by numerous modifications in structure and relation contemplated by this invention, drawings depicting the preferred forms of the invention have been annexed as part of this disclosure and in such drawings like 40 characters of reference indicate corresponding parts throughout all the views, in which—

Fig. 1 is a vertical sectional view of one 45 form of tiller composed of two parts, adapted to rotate in opposite directions but at substantially the same speed;

Fig. 2 is a detailed view showing substitute 50 gearing upon the driving and driven shafts whereby the two parts of the tiller will rotate in the same direction.

Referring now to the drawings in detail and more particularly to Fig. 1, 10 denotes a housing of any desired type mounted on the plow frame and provided with a plurality 55 of housing arms, one of which, 11, supports

bearings 12 for a main driving shaft 13. Another housing arm 14 supports roller bearings 15 for a sleeve 17 mounted on a tiller shaft 18. The upper end of the tiller shaft has keyed thereto a bevel gear 20 whereby they 60 rotate together, the gear being supported by bearings 21 within the housing cap 22. Likewise the sleeve 17 is provided with a bevel gear 23, both gears 20 and 23 being engaged by a gear 24 on the driving shaft 13. Thus, 65 it will be seen that the sleeve and the shaft are rotated at substantially the same speed but in opposite directions.

The lower part of the sleeve 17 is adapted 70 to carry a plurality of radially disposed tiller blades 25 disposed at varying angles and the lower part of the shaft 18 also carries blades 25, the blades being spaced apart one from another in any desired relation as by means of spacing collars 26. The particular type 75 of blade and spacing collar here used are immaterial and form no part of the present invention except as they broadly enter into certain combinations hereinafter set forth.

In Fig. 2 the driving shaft 13 is provided 80 with two bevel gears 27 adapted to engage bevel gears 28 and 30 on the sleeve 17 and shaft 18, respectively. This substitution for the gearing shown in Fig. 1 will permit the shafts to be rotated in the same direction and 85 as desired at different speeds by changing the gear ratios.

It will thus be seen from the above that the present invention contemplates a simple and practical tiller formed from a plurality of 90 individual parts whereby the disintegrator or tiller blades may be caused to rotate in the same or opposite directions and at the same or variable speeds as may be desired by a simple change of the gear ratios between 95 driving and driven parts.

The construction is simple and practical as well as reliable, durable and efficient in use and operation and the invention is believed to accomplish among others, all of the objects 100 and advantages herein set forth.

Without further analysis, the foregoing will so fully reveal the gist of this invention that others can, by applying current knowledge, readily adapt it for various applications without omitting certain features that, from the standpoint of the prior art, fairly constitute essential characteristics of the generic or specific aspects of this invention and, therefore, such adaptations should and 110

are intended to be comprehended within the meaning and range of equivalency of the following claims.

What I claim is:—

- 5 1. In a tillage implement, a substantially vertical two-part tiller shaft, disintegrator blades mounted on each part of said tiller shaft, a driving shaft common to the two parts of the tiller shaft, and gear means connecting the driving shaft and the two parts of the tiller shaft.
- 10 2. In an apparatus of the character described, in combination, a single substantially horizontal driving shaft, a two-part substantially vertical tiller shaft, blades associated with each part, an interchangeable power transmitting gearing between said driving shaft and the two parts of the tiller shaft, whereby the parts of said tiller shaft may be driven in the same or opposite directions at the same or variable speeds as desired.
- 15 3. In an apparatus of the character described, in combination, a single substantially horizontal driving shaft, a two-part tiller shaft, power transmitting means between the driving shaft and the two parts of the tiller shaft, and a housing enclosing said power transmitting means.
- 20 4. In an apparatus of the character described, in combination, a single driving shaft, a two-part tiller shaft, power transmitting means between the driving shaft and the two substantially vertical parts of the tiller shaft, said power transmitting means com-

prising gearing associated respectively with the two parts of the tiller shaft, said gearing being interchangeable for driving the parts of said tiller shaft in the same or opposite directions as desired.

5. In an apparatus of the character described, in combination, a single driving shaft, a two-part tiller shaft, power transmitting means between the driving shaft and the two parts of the tiller shaft, said power transmitting means comprising gearing associated respectively with the two parts of the tiller shaft, said gearing being interchangeable for driving the parts of said tiller shaft in the same or opposite directions as desired, one of the parts of said tiller shaft constituting a sleeve surrounding a portion of the other part.

6. In a tillage implement, a tiller mounted to rotate on a substantially vertical axis comprising a shaft on which the lower portion of the tiller is mounted to rotate, a sleeve enclosing the upper portion of the shaft and rotatable with relation to the shaft, bevel gears carried on the upper ends of said shaft and said sleeve with the gear faces confronting but spaced apart from each other, a substantially horizontal driving shaft, and a bevel pinion carried by the driving shaft and meshing with both of said bevel gears to thereby drive the shaft and the sleeve.

In testimony whereof I affix my signature.

THOMAS W. HICKS.
